UNITED STATES PATENT OFFICE.

GEORGE F. CUNNINGHAM, OF ALEXANDRIA, LOUISIANA.

FISHING TOOL.

Application filed September 1, 1921. Serial No. 497,479.

To all whom it may concern:

Be it known that I, GEORGE F. CUNNINGHAM, a citizen of the United States, residing at Alexandria, in the parish of Rapides and State of Louisiana, have invented certain new and useful Improvements in Fishing Tools, of which the following is a specification.

This invention relates to well appliances, and the primary object of the invention is to provide a novel fishing tool for facilitating the removal of well casings from oil wells and the like, said fishing tool being so constructed as to permit the ready lowering thereof into an operative position in relation to the casing to be removed and to permit the jaws thereof to be forced into positive engagement with the inner surface of the casing.

Another object of the invention is to provide an improved tool for removing well casings embodying a plurality of casing engaging jaws, means for normally holding the jaws in an inoperative position in relation to the well casing, whereby the tool can be readily lowered into or removed from a well casing, a novel means for forcing the jaws into an operative position in relation to the well casing, and a novel means for mounting the jaws whereby the same will be forced into tight engagement with the casing during the raising of the casing.

A still further object of the invention is to provide an improved well tool of the above character which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a longitudinal section through a well casing and improved tool, showing the jaws of the tool in their inoperative position taken on the line 1—1 of Figure 3.

Figure 2 is a similar view, showing parts of the tool in elevation and the jaws thereof slid into their positive locking position in relation to the well casing, so as to permit the raising or lowering thereof.

Figure 3 is a section through a casing and

tool, taken on the line 3—3 of Figure 1, and

Figure 4 is a section through the casing and tool, taken on the line 4—4 of Figure 1.

Referring to the drawings in detail, wherein similar reference characters designate corresponding parts throughout the several views, the letter A indicates the well casing; B, the novel tool for permitting the ready raising and lowering of the casing; and C, the means utilized for urging the jaws of the tool into operative position in relation to the casing A.

The casing A can be made up in the desired manner and may consist of the usual plurality of cylindrical pipe sections 5, which can be connected in the ordinary or any preferred manner.

The improved tool B includes the body D, the head E, the jaws F, and the means G for normally holding the jaws in their inoperative position.

The body D is of a hollow constriction and is shaped to conform to the cross sectional configuration of the casing A, and as shown includes the tubular sleeve 10, the upper end of which may be provided with tapered female threads 11, for the reception of a pipe section 12, to which the improved tool B can be attached. The lower end of the pipe section 12 is provided with the usual male threads 13.

The head E is carried by the lower portion of the tubular sleeve 10 and may be formed integral therewith. This head E includes a solid cylindrical body 15, which may have, as shown, a diameter less than that of the tubular sleeve 10.

The cylindrical body 15 has its periphery at equidistantly spaced points provided with grooves 16 for the reception of the jaws F, which will be hereinafter more fully described. The inner wall of the grooves 16 are gradually inclined downwardly toward their lower ends as at 17, for a purpose which will hereinafter more fully appear. The lower edges of the grooves 16 at the tapered portions thereof may be provided with inwardly extending seats 18 for the reception of rollers 19, which facilitate the sliding movement of the jaws F. The body 15 is also provided with an axial bore 20, the upper end of which is enlarged as at 21 for a purpose which will also hereinafter more fully appear.

The jaws F are of a wedge shape and are mounted for sliding movement in the grooves 16 and owing to the inclined rear

walls 17 of the grooves, the wedge shaped jaws F will be forced outwardly when the same are moved downwardly in a vertical plane in relation to the head E. The outer edges of these wedge shaped jaws F are serrated or provided with teeth 26, which are adapted to bite into the inner surface of the casing A, when it is desired to raise or lower the casing from or into the well hole.

10 The means G utilized for moving the jaws to their operative spread position and for holding the jaws in their inoperative position consists of the stem 30, which is slidably mounted within the axial bore 20. The 15 lower end of the stem 30 is externally threaded and fitted within a socket 31, formed in the conical shaped nose 32, which normally engages the lower surface of the body 15. The base portion of the conical nose 32 is 20 of substantially the same diameter as the body 15 and when the nose is in its normal position, the same closes the lower ends of the grooves 16, thereby preventing downward movement of the wedge shaped jaws F 25 in the grooves 16. The upper end of the stem 30 protrudes outwardly of the body 15 for a considerable distance and has formed integrally therewith or secured thereto in any preferred manner the head 35, which 30 constitutes the means for forcibly moving the jaws downwardly and outwardly into their operative well casing grasping position. This head 35 consists of a disc shaped plate 36, and a plurality of depending equidistantly spaced fingers 37. The lower ends of these fingers 37 are adapted to normally fit within the upper flared ends of the groove 16 directly above the wedge shaped jaws F. An expansion spring 38 is coiled about the 40 stem 30 and is disposed within the enlarged portion 21 of the axial way 20 and has its terminals engaging respectively the lower surface of the disc shaped plate 36 and a shoulder formed by the enlarged portion 21 of the axial way 20. It can be seen that this 45 spring normally tends to hold the head in its raised position and the conical nose in engagement with the lower face of the head E and thus normally prevent downward and outward movement of the jaws F.

When the head 35 of the means G is forced downwardly by the actuating device C, it can be seen that the conical nose 32 will be moved downwardly and away from the 55 lower face of the head E and that the fingers 37 will be moved into forcible engagement with the wedge shaped jaws F, thus moving the same downwardly in the grooves 16. The downward movement of the wedge shaped jaws F is permitted in the grooves by the rollers 19 and the inclined rear walls 17 of the grooves 16 will urge the wedge shaped jaws F outwardly into forcible gripping contact with the inner surface of the well casing, so that the casing may be readily 60 65

raised or lowered as the case might be. It can also be seen that the weight of the casing will normally tend to further move the wedge shaped jaws F toward the lower ends of the grooves 16, which, owing to the inclined rear walls 17 thereof will force the wedge shaped jaws F into tighter contacting position with the well casing.

70 The actuating means C utilized for moving the head 37 of the operating means G includes a weight 40, which may be of any desired size or configuration providing the same can have free movement within the pipe section 12, and is of such a mass as to operate the means G against the influence of 75 the coil spring 38. The upper end of the weight 40 may be provided with an eye 41, so that a cable or the like can be attached thereto and thus permit the ready raising and lowering of the weight into the wall 80 casing.

85 In use of the improved tool, when it is desired to lift the well casing, the sleeve portion 10 of the tool is threaded on to the pipe sections 12, and the device is then lowered into the well casing until the head E thereof reaches the desired point. At this time, the actuating member C is dropped into the well casing, and the weight coming into forcible contact with the head portion 90 95 35 of the operating means G will forcibly move the jaws F, as heretofore described, into engagement with the well casing. The pipe section 12 is then lifted in the usual manner and the jaws gripping the casing 100 A will permit the ready raising thereof.

When it is desired to release the jaws F from engagement with the well casing, it is merely necessary to lift the weight C and the spring 38 will tend to move the nose 32 105 upwardly and force the jaws back into their normal positions out of engagement with the well casing.

110 From the foregoing description, it can be seen that an exceptionally simple and durable fishing tool has been provided for permitting the ready removing of a well casing from a well hole, the tool being so constructed as to permit the ready lowering thereof into an operative position in relation to the 115 well casing, and to permit the jaws thereof to be readily moved into a spread well casing engaging position.

120 Changes in details may be made without departing from the spirit or scope of this 120 invention; but,

I claim:

1. A fishing tool comprising a body having a plurality of tapered guide ways therein, wedge shaped jaws slidably mounted in said guide ways, means for normally holding the jaws in an inoperative non-work engaging position in said guide ways, and means for forcibly moving said jaws outwardly into a work engaging position.

2. A fishing tool comprising a head having the periphery thereof provided with a plurality of spaced guide ways extending from the upper end to the lower end thereof, 5 a plurality of wedge shaped jaws slidably mounted in said guide ways, a sliding stem associated with said head, a nose carried by the lower end of the stem arranged to engage the lower edge of the jaws to prevent 10 movement thereof in said guide ways, and fingers carried by the stem for engaging the upper end of said jaws for moving the same downwardly into an operative work engaging position when the nose is moved away 15 from said jaws.

3. A fishing tool comprising a body, a plurality of slidable work engaging jaws carried by the body, means slidably associated with said body for holding the jaws 20 in a non-work engaging position against sliding movement, and means operatively connected to said first mentioned means for moving the jaws into a work engaging position upon operation of said second mentioned member.

4. A well fishing tool comprising a member, a plurality of slidable and radially movable jaws associated with said member, means engaging said jaws for preventing 30 sliding movement thereof and for holding the jaws in a non-work engaging position, and a plurality of rigid members operatively connected to said means and disposed in superimposed relation to said jaws for forcibly moving the jaws into a work engaging position upon actuation of said means, and means for moving first mentioned means in a downward position.

5. A well fishing tool comprising a member, a plurality of slidable and radially movable jaws associated with said member, means engaging said jaws for preventing 40 sliding movement thereof and for holding the jaws in a non-work engaging position, a plurality of rigid members operatively connected to said means and disposed in superimposed relation to said jaws for forcibly moving the jaws into work-engaging position upon actuation of said means, means 45 for moving said first mentioned means in a downward position, and resilient means for

normally holding said first mentioned means in a raised position against accidental movement.

6. A well fishing tool comprising a head, 55 having a plurality of tapered guide ways formed in the periphery thereof opening out at the upper and lower ends of the head, a sliding stem associated with the head, a nose carried by the lower end of the stem 60 arranged to normally abut the lower face of the head and close the lower ends of said guide ways, a plurality of wedge shaped jaws slidably mounted in said guide ways, a head carried by the upper end of the stem 65 including a plurality of depending fingers arranged to extend within said guide ways, spring means normally holding the stem, nose and last mentioned head in a raised position, and a weight for permitting the 70 downward movement of the stem and its cooperative parts against the tension of said spring means as and for the purpose specified.

7. A fishing tool for use in removing well 75 casings comprising a tubular body, a solid head formed on the lower end of the body having a plurality of equi-distantly spaced tapered guide ways formed therein opening out through the lower and upper faces of the head, the guide ways having notches formed therein, roller bearings fitted in said notches, tapered jaws slidably mounted in said guide ways, gripping teeth formed on the outer edges of said wedges, the head being provided with an axial way, a stem 80 slidably mounted in said axial way, a conical shaped nose carried by the lower end of the stem having a diameter substantially equal to the diameter of the head and arranged to normally close the lower ends of said guide ways to prevent downward movement of said tapered jaws, a disc carried by the upper end of the stem, a plurality of depending fingers carried by the periphery of the 85 disc arranged to extend in the upper ends of said guide ways, an expansion spring coiled around said stem arranged to engage the disc and said head, and a weight for operating said stem and cooperative parts against 90 the influence of said spring.

GEORGE F. CUNNINGHAM.
